UNITED STATES PATENT OFFICE.

EDGAR H. BRISTOL, OF FOXBORO, MASSACHUSETTS, ASSIGNOR TO THE FOXBORO COMPANY, OF FOXBORO, MASSACHUSETTS, A CORPORATION OF MASSACHUSETTS.

RETAINER FOR GLAZINGS AND THE LIKE.

Application filed March 31, 1925. Serial No. 19,749.

To all whom it may concern:

Be it known that I, EDGAR H. BRISTOL, a citizen of the United States, and a resident of Foxboro, county of Norfolk, and 5 State of Massachusetts, have invented an Improvement in Retainers for Glazings and the like, of which the following description, in connection with the accompanying drawings, is a specification, like characters on 10 the drawings representing like parts.

This invention relates to the retaining of members in frames and finds a particular application to the retention of the glazing in the door frame or bezel ring of such instruments as pressure gages, thermographs and the like.

My invention will best be understood by reference to the following description of an illustrative embodiment thereof shown by 20 way of example in the accompanying drawings, wherein:

Fig. 1 is a fragmentary perspective view of a portion of the door frame of a recording instrument showing a glazing clip illustrating of my invention; and

Figs. 2, 3 and 4 are sections illustrating successive steps in the application of the clip.

Referring to Fig. 1, I have there shown 30 a portion of the annular door frame of a recording instrument embodying the main cylindrical portion 5 and the inwardly extending annular flange 7 against which rests the glazing 9. The glazing may be clamped 35 in position by the use of a suitable number of retaining clips disposed at intervals around the door frame, one of the clips being illustrated in the figure.

The retaining clip may be made of a suitable 40 flexible and preferably somewhat resilient metal and may embody a base 11 of some length adapted to be presented to the inner surface of the part 5 of the frame. Adjacent the ends of this base 11 and projecting angularly therefrom, preferably at 45 a somewhat obtuse angle as illustrated in Fig. 2, are fingers 13 adapted to extend over and engage the glazing 9. The clip may be secured in position by means of a 50 clamping screw 15 passing through the base 11 substantially centrally thereof between the two fingers 13 and tapping into the body of the frame 5. The screw 15 may pass through a diagonal slot 17 in the base 11.

55 In the preferred form of the invention

shown wherein the fingers 13 extend outwardly at an oblique angle as shown in Fig. 2, the parts may be assembled as graphically illustrated in Figs. 2, 3 and 4. In Fig. 2 the clip is secured in position by the screw 15, which, however, is not set up. The clip may then be pressed circumferentially of the frame by a force applied to one end thereof and as the screw 15 slides in a slot 17 the clip as a whole will 60 be moved transversely toward the glazing 9, the fingers 13 being pressed against the glazing to the position shown in Fig. 3. It will be noted that the base 11 is so formed as to permit the circumferential sliding 65 movement and the resultant transverse movement due to the reaction of slot 17 and may move freely over the inner face of part 5. After this movement the clip as a whole 70 is positioned as shown in Fig. 3 somewhat 75 diagonally across the angle defined by the inner surface of the part 5 and the glazing 9. While the clip is held by its end against retrograde movement circumferentially the screw may be set up, drawing the clip home 80 in this angle and giving a final retaining pressure which may bend inwardly the 85 yieldable clamping fingers 13 in the manner illustrated in Fig. 4.

By providing the body 11 of considerable 90 circumferential length the oblique slot 17 may be provided which permits the adjustment described which both facilitates assembly and compensates for various thicknesses of glass, packing and the like irrespective of the position of the holes for the clamping screws. The fingers 13 are disposed at opposite ends of this relatively long base and provide two points of engagement 95 with the glass. This permits a slight swivelling of the clip as a whole about the single clamping screw 15 so that the pressure is equalized. The clamping pressure is further distributed at separated points over a comparatively large area of glass and the 100 pressure is inwardly of the edge thereof so that chipping is eliminated. The provision of the two clamping fingers 13 with the space between them permits the long body 11 of the clip to yield somewhat so that the pressure of the screw tends to clamp it against the curved surface of the frame 5, the clip 11 yielding with a resilient tension which exerts a lengthwise pull on the screw tending 105 to hold it locked against accidental 110

loosening. In spite of the length of the clip as a whole the fingers 13 may be made narrow and each may yield freely either to or beyond the position of Fig. 4.

Having described in detail the particular embodiment of my invention shown by way of example in the accompanying drawings and pointed out without attempting to be exhaustive a few of the advantages obtained, the features exemplified thereby which I claim as new and desire to secure by Letters Patent I shall express in the following claims.

Claims:—

- 15 1. In combination with a bezel or frame and a glazing received therein, a retaining member comprising an extended base provided with a surface presented to the frame capable of free sliding movement thereover, 20 a pair of angularly directed fingers at the extremities of the base to overlie the glazing and a substantially centrally located screw passing through said base and clamping it to the frame.
- 25 2. In combination with a bezel or frame and a glazing received therein, a retaining member comprising an extended base provided with a surface presented to the frame capable of free sliding movement thereover, 30 a pair of angularly directed fingers at the extremities of the base to overlie the glazing, said base having an oblique slot in the

central portion thereof and a screw passing through the slot for clamping said member to the frame.

35

3. In combination with a bezel or frame and a glazing retained therein, a clip comprising an extended base provided with a surface presented to the frame capable of free sliding movement thereover and having an angularly directed portion to bear on the glazing, said base having a diagonal slot and a clamping device passing through the slot and engaging the frame, the whole providing a structure wherein the clip may first be pressed lengthwise by a force applied to an end thereof and the angularly directed portion thereby pressed against the glazing and may then be secured by setting up the clamping device.

45

4. In combination with a curvilinear bezel or frame and a glazing received therein, a retaining member having a yielding base presented to the frame and normally adapted to extend cord-like across the curve thereof, a pair of angularly directed fingers at the extremities of the base to overlie the glazing and an attaching screw passing through said base between the fingers clamping it to the frame and bending it to the curve of the frame.

50

In testimony whereof, I have signed my name to this specification.

EDGAR H. BRISTOL.
